ABSTRACT OF THE DISCLOSURE

A mechanical latch designed for operation with a relatively small size electromagnetic contactor is connected for operation with a relatively large size contactor by utilizing a force dividing latch lever pivotally mounted at one end thereof to a fixed portion of the contactor. With the contactor mechanically latched, a point intermediate the ends of the lever, and preferably close to the pivot, engages the portion of the contactor carrying the movable contacts. The end of the lever remote from the lever pivot is engaged by the mechanical latch with this engagement being through a pawl pivoted to the lever and provided because of a space limitation.

This invention relates to electromagnetic contractors in general and more particularly relates to means for enabling a relatively small size mechanical latch to be utilized with a relatively large size contactor.

Mechanically held contactors are utilized where absolute quietness is required or where the customary hum from magnetically held contactors will be objectionable. The J. H. Herrmann et al. copending application Ser. No. 518,366 filed Jan. 3, 1966, now Patent No. 3,358,252 and assigned to the assignee of the instant invention discloses a mechanically held contactor with manual release. The latch unit of the aforesaid application Ser. No. 518,366, now Patent No. 3,358,252, is specifically adapted to be utilized with relatively small size contactors. For reasons of economy it is desirable to utilize this same relatively small size latch unit with relatively large size electromagnetic contactors. However, such relatively small size latch units will not function when in direct engagement with the movable contact carrier of a relatively large size contactor because of the combined forces of the return springs and contact pressure springs is too large.

The instant invention consists of utilizing a force dividing linkage to reduce the force reflected from the contactor back to the latch unit. In particular, the force dividing linkage is a lever pivotally mounted at one end thereof to a fixed portion of the contactor and is provided with a latching portion which engages the movable contact carrier. Because of space limitations a pawl pivotally mounted to the end of the lever remote from the contactor is interposed between the lever and the movable contact carrier.

Accordingly, a primary object of the instant invention is to provide novel means which permits a relatively small size mechanical latch unit to be utilized with a relatively large size electromagnetic contactor.

Another object is to provide a force diving linkage interposed between a relatively large size electromagnetic contactor and a relatively small size electromagnetically reusable latch means.

Still another object is to provide a linkage of this type mounted to the contactor on a fixed pivot and having a pawl mounted on the other end thereof to be directly engaged by the latch unit.

These as well as other objects of this invention will be

2

come readily apparent after reading the following description of the accompanying drawings in which:

FIGURE 1 is a side elevation showing a relatively small size mechanical latch unit and a relatively large size electromagnetic contactor in operative relationship with a force dividing linkage interposed therebetween in accordance with the teachings of the instant invention.

FIGURE 2 is a side elevation showing the elements of the force dividing linkage in the positions occupied thereby when the contactor is latched closed.

FIGURE 3 is a plan view of the elements of FIGURE 2 looking in the direction of arrows 3—3 of FIGURE 2.

FIGURE 4 is an exploded perspective of the significant elements of FIGURE 2.

FIGURES 5 and 6 are schematics showing the major elements of the devices in FIGURE 1. In FIGURE 5 the contactor is latched closed while in FIGURE 6 the contactor is open.

Now referring to the figures. Electromagnetically reusable mechanical latch unit 10 of FIGURE 1 is of the identical size and shape as the latch unit illustrated in the aforesaid copending application 518,366, now Patent No. 3,358,252. However, electromagnetic contactor 11 to which latch unit 10 is mounted is many times larger in size than the contactor of the aforesaid copending application 518,366, now Patent No. 3,358,252. In fact, the contact pressure springs 12 (FIGURES 5 and 6) and the movable contact carrier return springs 13 are so massive that the forces exerted thereby will not permit latch unit 10 to function properly when latching extension 14 thereof is in direct engagement with the movable contact carrier 15. Thus, a force reducing linkage consisting of lever 17 and pawl 18 is interposed between latch unit 10 and movable contact carrier 15.

More particularly, lever 17 consists of elongated arm portion 21, latch portion 22 in a plane parallel and offset with respect to arm 21, connecting section 23 perpendicular to and joining arm 21 to latch section 22, and bearing section 24 also offset from and parallel to arm 21. Rivet 25, extending through aligned apertures 26, 26 in arm 21 and ear 24 as well as through clearance aperture 27 in ear 28 of mounting bracket 30, provides a pivotal mounting for lever 17 at one end thereof. Main portion 29 of bracket 30 is at right angles to ear 28 and is provided with clearance apertures 31 which receives screws 32 fixedly securing bracket 30 to a stationary portion of contactor 11. One end 33a of torsion spring 33 engages tab 29a of bracket 30 while the other end 33b of spring 33 engages connecting portion 23 of lever 17. Spring 33 is wound about pivot 25 and is positioned in the space between arm 21 and ear 24 to bias lever 17 in a counter-clockwise direction, as seen in FIGURE 2, about pivot 25 as a center.

Rivet 36 pivotally mounts one end of pawl 18 to the ends of lever 17 remote from pivot 25 with this pivotal movement being limited because of the relative proportions of lever 17 and pawl 18. The end of pawl 18 remote from pivot 36 is provided with section 37 in a plane parallel to rivet 36 and positioned so that the edge thereof most remote from rivet 36 is engageable by projecting part 14 of latch unit 10 for latching contact 11 closed. Rounded embossment 37a extending rearward from section 37 is engageable with latch unit surface 10a during movement of lever 17. Nose 37b projecting at right angles from section 37 is engageable with fixed surface 11a of contactor 11 during pivoting of lever 17.

Latching part 22 of lever 17 is provided with notch 22a to receive edge portion 38a of extension 38 for member 40 which is fixedly secured to movable contact carrier 15 and retains movable armature 41 mounted to carrier 15. Projection 41a at the end of member 40 remote from extension 38 projects opposite to the project-

ing direction of extension 38 and, as is now well known in the art, in cooperation with a suitably shaped slot provides guidance for carrier 15 as contactor 11 is opened and closed.

With the elements previously described in the positions occupied when contactor 11 is open (FIGURE 6) movable contacts 51, 53 are separated from stationary contacts 52, 54, respectively. When contactor coil 55 is energized armature 41 is attracted and moves downward to the contactor closed position of FIGURE 5. This causes movable contact carrier 15 and all elements secured thereto to move downward. Initially, the motion of carrier extension 15a is transmitted to contacts 51, 53 through spring 12 but once contacts 51, 53 engage contacts 52, 54 continued movement of armature 41 causes loading of contact pressure spring 12. The latter tends to move contact carrier 15 to the raised position shown in FIGURE 6 wherein contactor 11 is open. By the time the contactor contacts are closed, the upper edge 38a of extension 38 is opposite notch 22a in latching part 22 of lever 17 so that spring 33 is effective to cause slight counterclockwise movement of lever 17 to a position wherein edge 38a is deep within latching recess 22a. Further, under these conditions the upper end of pawl 18 has moved below projecting part 14 of latch unit 10 so that spring 65 of latch unit 10 is free to drive projection 14 to the right to the latching position shown in FIGURE 5.

When contactor coil 55 is deenergized, upward movement of movable contact carrier 15 is blocked since latch unit extension 14 prevents upward movement of pawl 18 which in turn prevents clockwise rotation of lever 17. Since latching part 22 is much closer than pawl 18 to pivot 26, the forces exerted by return springs 13, 13 and contact pressure spring 12 appear reduced when applied to latch unit projection 14.

In order to open contactor 11, coil 64 of latch unit 10 is energized and attracts armature 63 of unit 10 to the left with respect to FIGURE 5. This moves the right-hand edge of latch unit extension 14 to the left of pawl 18. Now the forces of return springs 13, 13 and contact pressure spring 15 are effective to rotate lever 17 in a clockwise direction about pivot 25 and in so doing the position of recess 22a changes and latching part edge 22b moves to the left of extension 38 thereby permitting the latter to move upward opening the contacts of contactor 11. Pawl 18 also moves upward to a position blocking return of projection 14 to latching position upon deenergization of coil 64.

Thus it is seen that the instant invention provides force dividing means whereby return and contact pressure spring forces reflected back to a mechanical latch are greatly reduced thereby permitting a relatively small mechanical latch unit to be operated in coordination with a relatively large size electromagnetic contactor.

Although there has been described a preferred embodiment of this novel invention, many variations and modifications will now be apparent to those skilled in the art. Therefore, this invention is to be limited, not by the specific disclosure herein, but only by the appending claims.

The embodiments of the invention in which an exclusive privilege or property is claimed are defined as follows:

1. The combination of an electromagnetic contactor unit and an electrically releasable latch unit for maintaining said contactor unit closed; said contactor unit comprising a fixed section and a movable section, cooperating contact means having portions mounted to each of said sections; said latch unit including a latching portion; means biasing said latching portion to a latching position and an electromagnetic operator for moving said latching portion to a releasing position; a lever means; pivot means movably mounting said lever means to said fixed section; said lever means positioned and constructed to simultaneously engage said latching portion and said movable section when said latching portion is in said latching position and said movable section is in closed position wherein said contact means is closed with said latching portion blocking movement of said lever means to thereby mechanically prevent opening of said contact means.

2. A combination as set forth in claim 1 in which said contactor unit includes biasing means urging said lever about said pivot means as a center, additional biasing means acting to cause relative movement between said sections to an open position wherein said contact means is open; said additional biasing means exerting a greater force than said biasing means and in opposition thereto whereby the latter is overcome and said movable section operates to said open position when said latching portion is in said releasing position.

3. A combination as set forth in claim 2 in which said lever includes a latch portion which engages said movable section; said pivot means being at one end of said lever; said latch portion being intermediate the ends of said lever and closer to said one end than to the other end; said latching portion being operatively engageable with said lever at said other ends.

4. A combination as set forth in claim 3 in which there is a pawl connected to the other end of the lever and interposed between said lever and said latching portion.

5. A combination as set forth in claim 4 in which the pawl is pivotally connected at one end thereof to the other end of the lever for relative movement with respect to said lever.

6. A combination as set forth in claim 5 in which said fixed section and said latch unit having facing surfaces forming a narrow space therebetween wherein the other end of the pawl is disposed and confined to limited movement with respect to said lever.
